UNITED STATES PATENT OFFICE.

OTTO FREIMARK, OF MARTIN, OHIO.

RAIL-BRAKE.

1,273,212.

Specification of Letters Patent. Patented July 23, 1918.

Application filed August 17, 1917. Serial No. 186,789.

To all whom it may concern:

Be it known that I, Otto FREIMARK, a citizen of the United States of America, residing at Martin, in the county of Ottawa and State of Ohio, have invented certain new and useful Improvements in Rail-Brakes, of which the following is a specification, reference being had therein to the accompanying drawing.

10 This invention relates to a rail brake and has for its object the provision of a simple and effective brake which is adapted to be supported upon the truck of a railroad car and the like in such a manner as to permit 15 the same to be thrown immediately into engagement with the rails and thereby bring the car or truck to an immediate stop.

Another object of this invention is the provision of a simple and efficient rail brake 20 which will normally be supported or retained in a retracted position or out of engagement with the rail.

With these and other objects in view the invention consists of certain combinations, 25 constructions and arrangements of parts as will be hereinafter fully described and claimed.

In the drawings;—

Figure 1 is a side elevation of a truck having the rail brake applied thereto;

Fig. 2 is a transverse sectional view through a truck showing the bolster and the means for supporting the rail brake directly above the rails;

Fig. 3 is a vertical section through the rail brake and casing;

Fig. 4 is a top plan view of the rail brake;

Fig. 5 is a section taken on the line 5—5 of Fig. 3;

Fig. 6 is a section taken on the line 6—6 of Fig. 3.

By referring to the drawings it will be seen that 1 designates the truck of the usual construction which supports the wheels 2 and it should be understood that the brake casing 3 is suspended below the truck or bolster in any suitable or desired manner without departing from the spirit of the invention. The said supporting means for the casing 3 is of course not essential to the effective operation of the rail brake.

This casing 3 is provided with flanges 4 upon the sides thereof through which flanges 4 pass suitable securing means 5 for connecting the casing 3 to a suitable support. The casing 3 is provided with a

pocket portion 5 which pocket portion 5 is in turn provided with a plurality of spaced integral ribs 6, which ribs are provided with vertically extending sockets 7. 60 Plunger rods 8 are mounted within the sockets 7 and these plunger rods carry coil springs 9 as shown clearly in Figs. 3 and 5 of the drawings. The lower ends of these plunger rods 8 are provided with eyes 10 65 for fitting in the notches 11 formed in the inner ends of the brake shoes 12. Suitable pins 13 pass through eyes 10 of the rods 8 for firmly securing the rods to the shoes 12. The rod 8 is provided with an eye 14 upon 70 the upper end thereof and a suitable washer 15 is mounted upon each rod 8 and engages the upper end of the springs 9 for causing the springs to be compressed when the shoes 12 are forced downwardly. It should be 75 understood that the eyes 14 will constitute an effectual means for holding the washers 15 against accidental displacement from the rods 8. By carefully considering Fig. 3 it will be seen that the brake shoes 12 are pivotally mounted within the pocket portion 5 of the casing 3 by means of pivot pins 16.

A pressure block 17 is slidably mounted between the spaced integral ribs 6 as shown clearly in Fig. 3 of the drawings and this 85 pressure block 17 is provided with a plurality of sockets 18 formed therein within which sockets 18 are mounted plungers 19. The lower end of these plungers 19 engage the inner ends of the brake shoes 12 and 90 springs 20 are mounted in the sockets 18 and bear against the inner ends of the plungers 19 for causing the plungers 19 to yieldably engage the shoes 12. This block 17 is adapted to freely slide between the sides of 95 the casing 3 and between the ribs 6. The casing 3 is provided with an aperture 21 upon one side thereof through which aperture 21 passes the rocker arm 22. This rocker arm 22 is pivotally mounted upon a 100 pivot pin 23 between the arms 24 which are secured to one side of the casing 3. The rocker arm 22 extends through the slot 21 as above stated and rests upon the top of the block 17. The outer end of the rocker 105 arm 22 is engaged by means of an operating cable 25 which cable is connected to a ring 26, the ring 26 constituting a junction for the cables 25 extending upon the opposite sides of the car. It of course should be 110 understood that a brake is used upon each side of the car and in connection with each track,

it is only found necessary to describe in detail the mechanical construction and operation of one of these brakes. The ring 26 is engaged by means of an operating cable 27 which cable passes over a pulley 28 supported upon the bottom of the car by brackets 29. This cable 27 is connected to a suitable operating rod which operating rod is controlled by means of the ordinary air brake operating mechanism.

From the foregoing description it will be seen that a very simple and effectual brake has been produced which may be instantly thrown to an operative position by pulling upon the cables 27 thereby forcing the outer ends of the arms 22 downward upon the block 17 and causing the shoes 12 to be firmly forced into engagement with the rails over which the car may pass. It should be understood that the block 17 is normally urged in an upward position in engagement with the operating lever 22 through the medium of the spring pressed plungers 19. It should be further understood that under normal conditions the shoes 12 will be held out of engagement with the rails due to the action of the springs 9. However the shoes may be immediately thrown into engagement with the rails through the action of the lever 22 upon the block 17.

What is claimed is:—

1. A brake of the class described comprising a casing, a plurality of shoes pivotally mounted near their outer ends upon said casing, yieldable means engaging the inner ends of said shoes for normally holding the same in an inoperative position with respect to a rail, a sliding block yieldably engaging the inner ends of said shoes, and means engaging said sliding block for forcing said shoes downwardly to an operative position upon the rail.

2. A rail brake of the class described comprising a casing adapted to be supported

upon a car, a plurality of shoes pivotally mounted within said casing, means for yieldably holding said shoes in a retracted position and out of engagement with a rail, a sliding block yieldably supported upon the inner ends of said shoes, and means engaging said sliding block for forcing the same downwardly and thereby forcing said shoes downwardly into engagement with a rail.

3. A rail brake of the class described comprising a casing adapted to be supported upon a car, a plurality of shoes pivotally mounted within said casing, means for yieldably holding said shoes in a retracted position and out of engagement with a rail, a sliding block yieldably supported upon the inner ends of said shoes, a rocker arm, a plurality of arms secured to said casing, said rocker arm being pivotally connected to said arms carried by said casing, said rocker arm engaging said sliding block for forcing the same downwardly, and means connected to said rocker arm for swinging the same.

4. A rail brake of the class described comprising a casing, a plurality of shoes pivotally mounted within said casing, a plurality of spaced ribs carried within said casing, spring pressed plungers mounted within said ribs and engaging said shoes for normally holding said shoes in a retracted position, a sliding block interposed between said ribs, spring plungers mounted within said sliding block and engaging the inner ends of said shoes for yieldably supporting said block upon said shoes and means for engaging said sliding block for forcing said block downwardly and urging said shoes outwardly into engagement with a rail over which said truck is passing.

In testimony whereof I hereunto affix my signature.

OTTO FREIMARK.
